CLAIM

The ornamental design for a conduit bending tool, as shown and described.

DESCRIPTION

FIG. 1 is a front perspective view of a conduit bending tool, showing the new design.

FIG. 2 is an alternate front perspective view of the conduit bending tool;

FIG. 3 is a front elevation view of the conduit bending tool; FIG. 4 is a rear elevation view of the conduit bending tool; FIG. 5 is a right side elevation view of the conduit bending tool;

FIG. 6 is a left side elevation view of the conduit bending tool;

FIG. 7 is a top plan view of the conduit bending tool; and, FIG. 8 is a bottom plan view of the conduit bending tool. The broken lines in the drawings depict portions of the conduit bending tool which form no part of the claimed design.

1 Claim, 8 Drawing Sheets
